DUPLEX DIE HEAD

James Hervey Sternbergh, Reading, Pa.; Berks County Trust Company executor of said James Hervey Sternbergh, deceased

Application September 9, 1948, Serial No. 48,345

17 Claims. (Cl. 10—96)

1

This invention relates to improvements in die heads for chasing threads on pipe, and has for a principal object the provision of a die head having a set of chasers for one range of sizes of pipe and a second set of chasers for another range of sizes of pipe, the chasers of one of said sets being angularly displaced from the chasers of the other set.

Another object of the invention is the provision in a die head of one set of thread chasers for one range of sizes of pipe, and a second set of thread chasers for another range of sizes of pipe, the provision of a cam ring for the chasers in said first mentioned set, and a second cam ring for said second set of chasers, a pawl and a rack for fixedly setting said first ring for the several pipe sizes within its range, and a second rack adapted to be brought into cooperative relation with said pawl for fixedly setting said second ring for the several pipe sizes within its range, and means for disengaging one of said pawls from its rack as the other is moved into the range of its rack.

Other objects and advantages of the invention will be apparent to those skilled in the art upon a study of the following specification and the accompanying drawings.

Referring to the drawings which are given by way of example to illustrate the invention:

Figure 1 is a front elevation of my improved die head;

Figure 2 is a rear elevation of the die head showing the cross-head carrying cut-off and chamfering tools;

Figure 3 is a side elevation of the die head as seen from the left side of Figure 1 or the right side of Figure 2;

Figure 4 is a front elevation of the die head with the front plate removed and portions thereof in section to show details of the two cam rings and the chasers controlled by each;

Figure 5 is a perspective view of one of the chaser elements;

Figure 6 is a sectional view taken along the lines 6—6 of Figure 4;

Figure 7 is a sectional elevational view taken along the lines 7—7 of Figure 4;

Figure 8 is a fragmentary front view showing the pawl engaging the rack controlling setting of the chasers of one of said sets;

Figure 9 is similar to Figure 8 except that the front cam ring is being moved to set the other chasers of the other set, and showing how the pawl is automatically disengaged from the other

2

rack, thereby facilitating the setting of the chasers of the other set;

Figure 10 is a plan view looking down on the cam rings from above and showing the relation of the racks to the single pawl, and showing other details; and

Figure 11 is a sectional view showing the automatic release mechanism for releasing the pawl, the lever, and the chasers when the proper length of thread has been formed.

Referring first to Figures 1 to 3 inclusive, the die head body 10 has formed integral therewith a base 11 which is generally in the form of a pan, and formed integral with the pan 11 is a rectangular sub-base 12. An opening 13 extends through the pan and sub-base. Spaced slides 14 and 15 may extend downwardly from the sub-base 12.

A three-way valve 16 is supported on a straight nipple 17, and is provided with an operating handle 18. A curved nipple 19 is connected to the valve 16 and it extends downwardly and inwardly as seen in Figure 3 to deliver oil to the cut-off tool to be presently described. The valve 16 also has connected thereto a flexible conduit 20 which is, in turn, connected to a source of oil under pressure.

Referring now to Figure 7, the nipple 17 engages a threaded hole formed in a boss 21 formed on the body 10, and communicates with a cavity 22 formed in the body 10.

The body has an annular rim 23 formed thereon and in alignment therewith is a boss portion 24 which has an extension 25 which forms a locating boss for a counterbore 28 formed in one end of an annulus 26. The annulus 26 is secured to the body 10 by means of cap screws, one of which is shown at 27.

The annulus 26 has a counterbore 29 formed in the other end thereof to receive a die spacer and oil ring member 30. The annulus 26 also has slots 31 and 32 in vertical alignment (Figure 4) and slots 33 and 34 in horizontal alignment so that these slots are spaced 90° apart therein.

The annulus 26 also has formed therein slots 35, 36, 37 and 38. These slots are also 90° apart, and they are angularly displaced with respect to the first mentioned slots.

Reciprocally carried in the slots 31, 32, 33, and 34 are thread chasing tools 39, 40, 41, and 42 respectively, and reciprocally carried in the slots 35, 36, 37, and 38, are chasing tools 43, 44, 45, and 46 respectively.

In Figure 5, I show one of the chasing tools. This tool is designated by the numeral 39, and

it is identical in shape with the others in that set, namely 40, 41, and 42. It consists of a main body having thread forming cutters 47 which terminate in a chamfered face 48. The upper part has a portion cut away, leaving a shank portion 49, the upper end 50 of which is curved. Spaced apart from the surface 50 is an arcuate slot 51, both faces of which are curved about radii having a common center with the center about which the surface 50 is formed. The cutter portions 47 on the several tools are such that they cooperate to form a continuous thread on the work.

The chasing tools 43 to 46 inclusive in the other set are similar to the tool shown in Figure 5 with the exception that the curved groove 51 is replaced by a curved groove to fit the cams in the cam plate which controls them, as will presently be described. Also the curved end 50, and the chamfered face is oppositely disposed with respect to the position of the face 48.

The annulus 26 has a central bore 52 which is in alignment with a central bore 53 formed in the body 10. It also has a flat surface 54 (Figure 4) formed thereon and one edge of this surface has an undercut 55 to form a locating shoulder.

A bracket 56, secured on the annulus 26 by means of screws 57, has a depending portion 58 which engages said locating shoulder and is steadied thereby. The bracket carries an upright lug 59 which extends rearwardly, as seen in Figure 4, and carries on the face thereof buffer material 60. This lug forms a stop for the cam plate 61, as will now be described.

The bracket 56 also has formed thereon an upright lug 62 which carries on the face thereof buffer material 63. This lug extends forwardly in the path of and forms a stop for the cam plate 64. The cam plate 61 carries four cams, one for each of the chasing tools 43, 44, 45 and 46, one of these being shown by the numeral 65 and another by the numeral 65a. Since all of these are identical a detailed description of only one of them is deemed sufficient. Consequently the cam 65a will be described in detail.

The cam 65a includes an overhanging boundary web 66 which joins a radial web 67. The cam 68 is spaced apart and parallel to the web 66, and a groove 69 therebetween is adapted to accommodate the web 50a formed on the chaser, so that the surfaces 51 engage the cam, and the curved end surface 50 on the chaser engages the overhanging web 66.

The cam plate 61 has an interior bore 70 which forms a working fit on the annulus 26. A spring 71 has one end secured to the cam plate 61 by means of a screw 72 and has its other end secured to the base 11 by means of a screw 73. A second spring 74 has one end secured to the cam plate 61 by means of a screw 75 and the other end is secured to the base 11 by screw 76.

It will be noted from Figure 4 that these springs are inclined to the right and therefore they constantly urge the cam plate 61 in a counterclockwise direction and normally hold the web 67 in contact with the buffer material on the lug 59. For moving the cam plate 61 in a clockwise direction, a rod 77 has a threaded end 78. This threaded end extends downwardly and engages a tapped hole formed in the cam plate 61, and thus the rod 77 forms a handle to be used in setting one set of chasers for different sizes of pipes. As the cam plate is rotated in a clockwise direction by means of the handle 77 the cam 68 which engages the slot 51 in the chasers moves them

inwardly (radially) and thus these chasers are set to thread different sizes of pipe.

In order to set the chasers for definite sizes of pipe a sector 80 is secured to the cam plate 61 by means of screws 79. The sector 80 intermediate the space between the screws 79 is thicker radially and is provided with a series of notches 81. The sector 80 may be seen in a plan view in Figure 10, and it will be noted that the notches 81 indicate pipe sizes as follows: 1", 1 1/4", 1 1/2" and 2". These settings are effected when the notch 81, indicating the desired size of pipe, is engaged by a pawl 82 which will presently be described.

The second cam plate 64 has an interior bore 83 which forms a working fit on the annulus 26, and this cam plate has a cam for each of the chasing tools 39, 40, 41 and 42. It has been pointed out above that one set of chasers has the threads 47 and clearance 48 reversed so that the cam groove therein extends forwardly, as viewed in Figure 4, instead of rearwardly, as was the case for the chasers 43, 44, 45 and 46. The cams for the chasers 39, 40, 41 and 42 are identical, and it is therefore believed that only one of them need be described in detail.

Each cam consists of an overhanging web 84, and a camming web 85 parallel thereto and in spaced apart relation therewith. Between the webs 84, 85 is a cam groove 86. The portion 50a on the corresponding chaser engages the groove 86, and the end surface 50 engages the inner face of the web 84 (Figures 4 and 7).

Referring now to Figure 4, the web 84 joins and has formed integral therewith a radial web 87, and the radial web 87 of the corresponding cam which controls the chaser 39 normally engages the buffer material 63 carried on the lug 62.

For urging the cam plate 64 in a counterclockwise direction a spring 88 has a loop 89 formed on one end thereof and this loop extends through a slot 90 formed in the web 87. The other end of the spring 88 is secured to the annulus 26 by means of a screw 92. A second spring 93 is oppositely disposed to the spring 88 and it has one end secured to the annulus 26 by means of a screw 94, and it has a loop 95 which engages a hole in the corresponding web 87 of the cam for moving the chaser 41.

The cam plate 64 has a handle 96 which may consist of a rod which threadedly engages a tapped hole in the cam plate 64 similar to the mounting of the handle 77 described above. The cam plate 64 has secured thereto by means of screws 97 a sector 98. The mid portion of the sector 98 between the screws 97 is somewhat thicker and it is provided with notches 99 for indicating definite pipe sizes so that the operator may set the chasers 39, 40, 41 and 42 for pipe sizes of 1/2" and 3/4", as indicated in Figure 10. The operator, by moving the handle 96 in a clockwise direction, causes the chasing tools 39, 40, 41 and 42 to move toward the center of the opening 52 and in the present arrangement the settings are for 1/2" and 3/4" pipe. The pawl 82 above described is of sufficient width that it may engage either the notches 81 in the sector 80 or the notches 99 in the sector 98.

Referring to Figure 10, it will be noted that the pawl is in engagement with the notch in the sector 80 which indicates a setting of the chasers 39, 40, 41 and 42 for threading 1 1/2" pipe.

Now, suppose the operator grasps the handle 96 and rotates the cam plate 64 to make a set-

ting for $\frac{3}{4}$ " pipe, for example, the following occurs: As he rotates the cam plate 64 in a clockwise direction the leading screw 97 which screws the sector 98 to the cam plate engages the pawl 82 and cams it upwardly, thereby disengaging it from the notch 81 representing the $1\frac{1}{2}$ " setting, and this allows the cam plate 61 to rotate in a counterclockwise direction under the urge of its springs 71 and 74, and when the web 67 encounters the buffer material 60 on the lug 59 the cam plate 61 is arrested in this position. As the operator continues to move the cam plate 64 in a clockwise direction it reaches a point where the pawl 82 engages the notch 99, which is labeled $\frac{3}{4}$ and he has the setting for $\frac{3}{4}$ " pipe.

A bracket 100 secured on the body 10 is provided with spaced lugs 101 and 102 to receive an adjustable stud 103 on which a lever 104 having a handle portion 105 is pivotally mounted on a pin 131 which passes through the lever 104 and an eye on the stud 103. The pawl 82 is pivotally mounted on a pin 106 carried by the lever 104. A hexagonal nut 107 which threadedly engages corresponding threads formed on the stud 103 is positioned between the lugs 101 and 102, and may be operated for advancing or retracting the stud in the lugs to effect a fine adjustment of the position of the pawl 82 in order to accurately position the chasers in accordance with whether the threads on the work shall be exactly the sizes indicated by the scale graduations or whether the threads shall be larger or smaller than said sizes. A lock nut 108 threadedly engages the stud 103 and is provided for locking the stud and maintaining any desired adjustment.

The automatic release mechanism for the pawl 82 and the lever 104, and consequently for the chasers, comprises a plunger 109 slideable in a sleeve 110 mounted on a radial bore in the body 10 and an aligned bore in a boss 111 on the bracket 100. Suitable means are provided for securing the sleeve 110 and for preventing rotation of the plunger 109. For example, a set screw 112 extends through the boss 111, the sleeve 110 and engages a key way formed in the plunger 109. The plunger 109 has an upper portion 113 formed with a central bore within which is secured a stem 114 and surrounded by a coiled spring 115 mounted between the base of the bore and an annular shoulder 116 on the sleeve 110. The spring 115 biases the plunger 109 upwardly so that when the plunger is released, a stud 117 carried thereby engages and operates the lever 105 to release the pawl 82 and permit the springs 71 and 74 to retract the chasers 39, 40, 41 and 42, if they are the ones in use; or to permit the springs 88 and 93 to retract the chasers 43, 44, 45 and 46, if they are the ones in use.

As shown in Figure 11, the stud 117 is moved transversely of the plunger 109 to and from an operative position relative to the lever 105, and a ball detent 118 is provided for holding the stud in either an operative or a non-operative position.

The stem 114 on its lower end is enlarged and carries a cross-pin pivotally supporting a work engaging finger 119 which extends into the bore 53 of the die head. The finger 119 has a stepped face 120 suitably formed to be engaged by the end of any size pipe within the capacity of the die head for causing the retraction of the chasers when the standard length of thread upon a piece of pipe is completed. A leaf spring 121 biases the finger about its fulcrum 122 to the work engaging position and, when the plunger 109 is de-

pressed, into engagement with a locking latch or pin 123 mounted in the die head body 10 and extending through a slot 124 in the plunger, and engages a shoulder 125 on the finger 119 for locking the plunger 109 in the depressed position. In operation the plunger 109 is depressed and locked by the engagement of the locking pin 123 with the finger 119. Either the cam plate 61 or the cam plate 64 is rotatably adjusted to a setting cutting threads on the size of pipe being worked upon and is locked in such position by the engagement of the pawl 82 with the corresponding notch in the sector 80 or 98. When the plunger is so depressed and locked the stud 117 is beneath the handle of the lever 105. When the proper length of thread has been cut the end of the pipe acting on the finger 119 disengages the latter from the pin 123 whereupon the plunger 109 is raised and is moved radially outwardly by the spring 115. The stud 117 carried by the plunger engages and raises the lever 105, thereby moving the pawl 82 out of engagement with the notch in the member 80 or the member 98, and the springs 71 and 74 cause the cam plate 61 to return to its normal position if the chasers being used are the chasers 43, 44, 45 and 46; or the springs 88 and 93 cause the cam plate 64 to return to its normal position if the chasers 39, 40, 41 and 42 are used in chasing these threads. Each cam plate, when returning to its normal position, withdraws the chasers associated with it from the cutting zone.

A post 126 has a shank which threadedly engages a threaded hole in the plate 64, and consequently the post extends radially from the surface of the plate. A threaded hole formed in the post is engaged by threads formed on the shank 127 of a screw which has a disc-like head 128. The threaded shank 127 also carries a lock nut 129, the purpose of which will be presently described.

The sector 98 has a lateral slot 130 formed therein and the disc-like head 128 forms a working fit with this slot. Now, for obtaining accurate adjustments of the cam plate 64 so that the settings, when either of the notches 99 is engaged by the pawl 82, the lock nut 129 may be loosened and the disc head 128 may be rotated in either direction, after the screws 97 have been slackened, until the desired adjustment is obtained. After this adjustment is obtained the lock nut 129 may again be tightened to retain the adjustment, and then the screws 97 may be tightened to hold the sector 98 in positive engagement with the cam plate 64. A closure plate 145 which has a central hole 146 therein which matches the bore 52 and which has a bevel 147 formed thereon is secured to the annulus 26 by means of screws 148.

On the rear face of the body 10 is provided a web 132 which forms a guide way. Facing the web 132 in spaced relation thereto is a short guide web 133, and in alignment with this guide and spaced apart from it is a second guide web 134. A portion of the web 132 and the web 133 form ways for a V-block 135, and another portion of the web 132 and the web 134 form ways for a V-block 136. The V-block 135 is provided with a left hand nut which engages a section of left hand thread 137 on the screw shaft 138, and the V-block 136 has a right hand nut 139 which engages a right hand threaded section 140 of the screw shaft 138. The shaft 138 is provided with a bearing 141 and secured on the end of the shaft is a handle 142 which when rotated in one direction moves the V-blocks toward each other, and

when rotated in the opposite direction it moves the V-clocks apart. A cross slide 143 may carry chamfering, facing, reaming and/or cut off tools. This cross slide includes a nut to engage threads (not shown) on a screw shaft which may be manually rotated by a handle 144.

It is most desirable that the pipe ends be cut off, chamfered and reamed before threading because ragged or burred edges may catch upon or damage the release finger 119 or cause it to release the plunger 109, and thereby retract the chasers before a full length of thread has been cut. It is also recommended that in chamfering the outer edges of the pipe ends, the cut should be substantially as deep as the root of a thread.

Although I have herein shown and described by way of example one embodiment of the invention, it is obvious that many changes may be made in the arrangements herein shown and described without departing from the spirit of the invention.

What is claimed is:

1. In a die head, a body, a set of chasers movably supported thereon, a member rotatably carried on said body for moving said chasers into and out of operative positions, a second set of chasers movably supported in said body, a second member rotatably carried on said body for moving said last chasers into and out of operative positions, a first notched sector mounted on said first movable member, a second notched sector mounted on said second movable member, a pawl carried on said body and common to the notches in both said sectors, whereby the chasers of either of said sets may be set and locked in operative positions by the engagement of said pawl with a notch in either of said sectors.

2. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them into and out of operative positions, a first sector mounted on said first movable member and having notches formed therein, a second sector mounted on said second movable member and having notches formed therein, a pawl carried on said body and common to the notches in both said sectors, whereby either of said sets of chasers may be set and locked in predetermined operative positions by the engagement of said pawl with a notch in either of said sectors.

3. A die head according to claim 2, in which one of said sectors is in advance of the other so that collectively said notches are in series.

4. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them into and out of operative positions, a first sector mounted on said first movable member and having notches formed therein, one notch for each operative position of said first set of chasers, a second sector mounted on said second movable member and normally in advance of the other sector, said second sector also having notches formed therein one for each operative position of said second

set of chasers, a lever mounted on said body, a pawl carried by said lever common to the notches in both said sectors, whereby either of said sets of chasers may be set and locked in operative positions by the engagement of said pawl with a notch in either of said sectors.

5. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them into and out of operative positions, a first sector mounted on said first movable member and having notches formed therein, one notch for each operative position of said first set of chasers, a second sector mounted on said second movable member and normally in advance of the other sector, said second sector also having notches formed therein one for each operative position of said second set of chasers, a lever pivotally mounted on said body, a pawl carried by said lever common to the notches in both said sectors, whereby either of said sets of chasers may be set and locked in operative positions by the engagement of said pawl with a notch in either of said sectors, automatic work controlled means for actuating said lever to disengage said pawl from a notch with which it is engaged, and means operative on the disengagement of said pawl for causing the member interconnected with the chasers in the operative position for moving them to an inoperative position.

6. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them into and out of operative positions, a first sector mounted on said first movable member and having notches formed therein, one notch for each operative position of said first set of chasers, a second sector mounted on said second movable member and normally in advance of the other sector, said second sector also having notches formed therein one for each operative position of said second set of chasers, a lever pivotally mounted on said body, a pawl carried by said lever common to the notches in both said sectors, whereby either of said sets of chasers may be set and locked in operative positions by the engagement of said pawl with a notch in either of said sectors, a depressible plunger mounted in said body, means actuating upon said plunger for biasing the latter to a raised position, work releasable latching means for holding said plunger in a depressed position, and a stud mounted on said plunger and moved by said plunger along a path spanned by said lever, and adapted when said plunger is released to operate said lever for engaging said pawl from a notch with which it is engaged, and movable with said plunger on the depression thereof to permit said lever to move said pawl into position to engage one of said notches, said stud being movable in said plunger to a position away from said path for enabling movement of said lever to engage said pawl with one of said notches without effecting the depression of said plunger.

7. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them into and out of operative positions, a first sector mounted on said first movable member and having notches formed therein, one notch for each operative position of said first set of chasers, a second sector mounted on said second movable member and normally in advance of the other sector, said second sector also having notches formed therein one for each operative position of said second set of chasers, a lever pivotally mounted on said body, a pawl carried by said lever common to the notches in both said sectors, a depressible plunger mounted in said body, said lever being movable to engage said pawl with one of said notches when said plunger is depressed, a finger pivotally carried by the inner end of said plunger and adapted to be positioned in the path of the work for actuation thereby when said plunger is depressed, latching means engageable with said finger to hold said plunger in a depressed position, means for moving said plunger to a raised position when said finger is deactivated by said work to disengage said latch, means carried by said plunger for actuating said lever on the raising of said plunger to unlock the member interconnected with the set of chasers in the operative position, and means for actuating said last member to move the chasers from the operative position to an inoperative position.

8. In a die head, a body, a set of chasers movably supported therein, a member rotatably carried on said body and interconnected with said chasers for moving them into and out of operative positions, a second set of chasers movably supported in said body, a second member rotatably carried on said body and interconnected with said last chasers for moving them in and out of operative positions, complementary locking means carried in part on said body and in part on said members for locking either of the latter to retain the set of chasers interconnected therewith in operative positions, a depressible plunger mounted in said body and movable radially therein, means carried on said plunger and adapted to unlock said locking means, a pivoted finger carried on the inner end of said plunger and adapted to be positioned in the path of the work when said plunger is depressed, a latching pin engageable with said finger to hold said plunger in a depressed position, said finger being adapted to be disengaged from said pin by the work, and means acting upon said plunger for moving it to the raised position for effecting the unlocking of said locking means.

9. In a die head, a body, a set of thread chasers movably supported therein, a die plate rotatably carried on said body and having follow cams thereon engaging said chasers for moving them into and out of operative positions, a second set of chasers movably supported in said body, a second cam plate rotatably carried on said body and having follow cams therein engaging said last chasers for moving them in and out of operative positions, a depressible plunger mounted in said body and movable radially therein, a stud carried by said plunger, a first sector mounted on said first cam plate and having notches formed therein corresponding to said first operative posi-

tions, a second sector mounted on said second cam plate and normally in advance of said first sector, said second sector also having notches formed therein corresponding to said second operative positions, a lever mounted on said body, a pawl carried by said lever and common to both said sectors and engageable with the notches of either of said sectors for locking either set of chasers in an operative position, a depressible plunger mounted in said body, a stud carried by said plunger for operating said lever to release said pawl from engagement with one of said notches, a pivoted finger carried by said plunger and adapted to be positioned in the path of work when said plunger is depressed, latching means cooperating with said finger to lock said plunger in a depressed position, said finger being adapted to be unlatched by the work on the completion of a working operation, means operative upon the unlatching of said finger to actuate said plunger for causing disengagement of the pawl from the notch with which it is engaged and spring means connected with said body and with said cam plates for actuating either one of them to move the set of chasers controlled thereby to an inoperative position.

10. In a die head, a body, a set of chasers thereon, means including a member movable on said body for moving said chasers into and out of operative positions, a second set of chasers in said body, means including a second member movable relative to said body for moving said second set of chasers into and out of operative position, a pawl carried by said body, a notched sector mounted on and movable with said first member, and a second notched sector mounted on and movable with said second member, whereby either of said sets of chasers may be set and locked in a selected operative position by engaging said pawl with one of the notches on either of said sectors.

11. In a die head, a body, a set of chasers thereon, means including a member movable on said body for moving said chasers into and out of operative positions, a second set of chasers in said body, means including a second member movable relative to said body for moving said second set of chasers into and out of operative position, a pawl carried by said body, a notched sector mounted on and movable with said first member, a second notched sector mounted on and movable with said second member, whereby either of said sets of chasers may be set and locked in a selected operative position by engaging said pawl with one of the notches on either of said sectors, and camming means carried by at least one of said members for disengaging said pawl from a notch in the sector on the other of said members, when the latter had been previously set for an operation, thereby releasing its set of chasers and permitting the other set of chasers controlled by said one of said members to be set and locked for a different operation.

12. In a die head, a body, a set of chasers thereon, means including a member movable on said body for moving said chasers into and out of operative positions, a second set of chasers in said body, means including a second member movable relative to said body for moving said second set of chasers into and out of operative position, a pawl carried by said body, a notched sector mounted on and movable with said first member, a second notched sector mounted on and movable with said second member, whereby either of said

11

sets of chasers may be set and locked in a selected operative position by engaging said pawl with one of the notches on either of said sectors, and means carried on said body for performing initial operations on the end of the work for facilitating a thread chasing operation thereon.

13. A die head according to claim 4, in which adjustable means is provided between said body and said pawl, operating through said notched sectors, and connections between said rotatable members and the chasers controlled thereby to produce appropriate settings of said chasers for corresponding sizes of pipe threads.

14. A die head according to claim 4, in which at least one of said sectors is adjustably mounted on its rotatable member whereby said sector may be set and secured with any one of its notches in engagement with said pawl to insure that the corresponding setting of the chasers controlled by said last member produces the correct thread size indicated for the notch engaged by said pawl.

15. A die head according to claim 4, in which said first sector is fixed on said first mentioned member and said second sector is adjustably carried on said second member, adjustable and lockable means being provided between said body and the lever supporting said pawl, whereby said adjustable and lockable means is employed to correctly set the pawl to control the position of said first sector and its notches, thereby correctly positioning the die set which it controls.

16. A die head according to claim 4, in which the second of said sectors is adjustably mounted

on its rotatable member, whereby the same may be adjusted on its rotatable member to effect correct settings of said second set of chasers, so that after said sector has been properly adjusted with the pawl in any one of its notches to correctly position said second set of chasers for cutting the corresponding size of pipe thread, it may be locked so that thereafter setting the pawl in any of the notches of that sector sets the chasers for the corresponding size of pipe thread cutting.

17. A die head according to claim 4, in which said first sector is fixed on said first mentioned member and said second sector is adjustably mounted on said second member, adjustable and lockable means being provided between said body and said pawl, whereby said adjustable and lockable means is employed to set the pawl to control the notches in said sectors so that the die set controlled by the first sector, its rotatable member and inner connections thereof, will be correctly positioned for cutting thread sizes corresponding to its several notches, while the second sector being adjustably mounted on the second rotatable member is then so adjusted and set as to similarly control the second set of dies for the several settings required of them for the cutting of corresponding sizes of pipe threads.
